HILBORNE L. ROOSEVELT, OF NEW YORK, N. Y.

Letters Patent No. 88,909, dated April 13, 1869.

IMPROVEMENT IN ELECTRIC ORGAN-ACTION.

The Schedule referred to in these Letters Patent and making part of the same.

To all whom it may concern:

Be it known that I, HILBORNE L. ROOSEVELT, of the city, county, and State of New York, have invented a new and improved Electric Organ-Action; and I do hereby declare that the following is a full, clear, and exact description thereof, which will enable others skilled in the art to make and use the same, reference being had to the accompanying drawings, forming part of this specification.

The object of this invention is to apply electricity from a battery, or other source to the operation of organs, so that the keys can be played at a suitable distance from the organ, and without any difficulty.

The invention consists, first, in providing a separate battery for each octave of the organ. It is necessary in every magnetic action applied to organs to have sufficient battery-power to actuate at least ten magnets, (sometimes more,) at one and the same time, and it must also be remembered that the lower notes require much more power than the upper ones. Now, the battery-power necessary to enable the organist to play chords, must, if thrown upon single notes, (as it would be when running passages are played,) destroy the connections by burning, in spite of the best-contrived circuit-breakers, and must also waste the battery. To avoid this difficulty, I divide the notes into octaves with a separate battery for each separate octave. Take for example the octave from middle C to C above, on which the organist never holds more than five notes at one and the same time, and I apply a separate battery, say of six Smees, or other cups, with appropriate connections, which is enough to do all the necessary work, and actuate all the required magnets on that octave, without burning or waste of the battery; and so on for each separate octave, according to its separate requirements.

The invention consists, second, in the use of glycerine, which is placed upon the mercury to prevent its evaporation, and which protects the point of the key-wire from oxidation, while the same is lifted out of the mercury.

The invention further consists, in providing a connection between the pedal and key-wires, so that by means of the pedal, the pallets of key and pedal can be operated at once. This connection is a sliding wedge, or equivalent mechanism, by means of which the mercury-cups of key and pedal are united by a wire dipped into both, to cause a current from the key-battery to be opened and closed by the action of the pedal.

The invention further consists, in the combination of the armature with the swinging pallet, as will be hereinafter more fully described.

The invention also consists, in the application of a sliding pallet drawn longitudinally by the armature, whereby less friction is produced than by the ordinary swinging pallet.

The invention finally consists, in providing a sepa-

rate battery, or at least a separate set of wires, and a separate mercury-trough for each octave of the organ or other suitable subdivision of the same, for the purpose of economizing the power of the battery, which would be uselessly wasted were it to be used in full force for each key, and for better preserving the connections.

In the accompanying drawings—

Figure 1 represents a sectional side view of the wire connections and mercury-troughs, as arranged on a key and pedal of an organ, the said key and pedal being separated.

Figure 2 is a similar view, showing the key and pedal in electric connection.

Similar letters of reference indicate corresponding parts.

A in the drawing, represents one key of a piano-forte action.

Above the keys, or in any suitable other position, is arranged a fixed transverse trough, or vessel, B, which is made of separate pieces, or divided into sections, so that one piece, or section will suffice for each octave, or other subdivision of the bank of keys.

This trough is partly filled with mercury, glycerine being placed above the mercury into the trough, to cover the liquid metal, and to prevent it from evaporating.

C is a pallet, or valve of the organ. It is hinged at a as usual, and has a projecting arm, b, to which the armature D of a pair of intensity coils, E E, is secured.

When the coils are charged, they attract the armature, and cause the pallet to swing open, the power of the charge overcoming the action of a spring, O.

If the armature would be fastened directly to the body of the pallet, it would in its straight motion tend to strain and injure the hinge of the same, which is avoided by the use of the arm b.

The coils E E are connected by one wire F, with one pole of a battery, G, and by another wire H, with the key A.

A wire, I, from the battery G, is constantly dipped with its end in the mercury.

The end of the wire H is raised out of the mercury as long as the key is pressed up by a spring, d.

When, however, the key is pressed down, the end of H is also dipped into the mercury, and a metallic connection is established between the wires H and I, so that a current may pass from the battery through the coils E, to charge them, and to cause the opening of the pallet.

When the key is released, it is at once raised by the spring d, to throw the wire H out of the mercury.

The circuit is then broken, and the pallet closed by the spring c.

J is one of the pedals.

Above the pedals is arranged a stationary mercury-

trough, K, which is filled with mercury and glycerine, like the trough B, and into each section of which the end of a wire, L, from a battery, M, is dipped.

To the pedal is fastened a wire, N, which connects with helices O, the armature P of which is fastened to a pallet, Q, while the helices are also directly connected with the battery M by means of a wire, R.

The pedal is thrown up by a spring, e. When its inner end is depressed, the end of its wire N is dipped into the mercury, and a current is established to open the pallet Q, the operation being just like that described in connection with the key.

The glycerine on the mercury protects and surrounds the ends of the wires H and N, while the same are raised out of the mercury to prevent their injury.

Glycerine being a non-conductor of electricity, has the property when poured on the mercury of diminishing the burning by the sparks, and also of checking the evaporation of the mercury.

A wire, S, may be arranged to connect the two troughs B and K, so that one of its ends may constantly be dipped in one of the mercury layers.

The other end may be forced into the respective other trough, by means of a wedge-shaped slide, J, which is shown in both figures.

In fig. 1, it is represented as pushed in to not affect the lower end of the wire S, which is raised out of the mercury of the trough K.

In fig. 2, it is represented as drawn out to force the lower end of the wire into the mercury of K.

A wire, U, is attached to the pedal J, and connects the same with the key-coils E. It is with its end raised out of the mercury in K, when the pedal is raised, as in the drawing. But when the pedal is depressed, its end is dipped in the mercury.

Then a connection is established through the wires

I, S, and U, with the coils E, to cause the opening of the pallet C. Thus, when the key is raised, a current may at once be established through both sets of coils, by working the pedal alone, in order to open at once the pedal and key-pallets, or at least any desired number of the latter.

The pedal-pallet Q is represented as a perforated sliding pallet, which I prefer on account of its greater simplicity, and because it produces less friction during operation.

I do not claim broadly an electric organ-action, as I am aware that the same is not new.

I claim as new, and desire to secure by Letters Patent—

1. The application of a separate battery to each separate octave of an organ, substantially as described for the purpose specified.

2. Covering the mercury in the cups B and K, or in either, with glycerine, substantially as and for the purpose herein shown and described.

3. The wire S and the sliding wedge T, or its equivalent, when arranged substantially as described, for the purpose of connecting the mercury-cups of key and pedal, to allow the pallets of both to be worked by the pedal alone, as specified.

4. The pallet C, constructed as described, in combination with the armature P, as herein set forth for the purpose specified.

5. The sliding pallet Q, when arranged and operating substantially as and for the purpose herein shown and described.

HILBORNE L. ROOSEVELT.
